UNITED STATES PATENT OFFICE.

EDWARD J. GRANGER, OF CHICAGO, ILLINOIS, ASSIGNOR TO DAVID S. GARDNER, OF CHICAGO, ILLINOIS.

FOLDING AND PLAITING MACHINE.

1,260,766.

Specification of Letters Patent. Patented Mar. 26, 1918.

Application filed March 26, 1917. Serial No. 157,515.

To all whom it may concern:

Be it known that I, EDWARD J. GRANGER, a citizen of the United States, and a resident of the city of Chicago, in the county of Cook and State of Illinois, have invented certain new and useful Improvements in a Folding and Plaiting Machine; and I do hereby declare that the following is a full, clear, and exact description of the same, 10 reference being had to the accompanying drawings, and to the numerals of reference marked thereon, which form a part of this specification.

This invention relates to a machine designed for the purpose of plaiting, folding or crinkling strips of paper, preferably strips which have been perforated transversely, so that when the strip is plaited longitudinally, the small plaited sections of 15 the strip may be detached from one another.

It is an object therefore of this invention to construct a machine adapted to receive paper strips laid thereon, and to move the strips between creasing rolls, thereafter compressing the strips to form plaits or folds therein, and to hold the same against a heated surface in order to set the folds in the strip and thereafter discharge the same from the machine.

It is also an object of this invention to construct a machine adapted to fold material into accordion plaits and to tightly compress and crease the same against a heated surface so as to permanently set the 25 folds therein, finally positively discharging the material from the machine, coincident with a return of the parts of the machine to normal for the reception of additional material.

It is furthermore an important object of 30 this invention to construct a machine adapted to receive material laid thereon, to feed the same between creasing rollers, and thereafter compress the same under spring 35 pressure against the heating plate, which is subsequently withdrawn from the strip to permit positive ejection of the strip from between its feeding means and said heating plate in plaited condition.

Other and further important objects of 40 the invention will be evident from the disclosure in the drawings and specification.

The invention (in a preferred form) is illustrated in the drawings, and hereinafter more fully described. 55

On the drawings:

Figure 1 is a top plan view of a machine embodying the principles of my invention.

Fig. 2 is a side elevation thereof.

Fig. 3 is a sectional detail on line 3—3 of 60 Fig. 1.

Fig. 4 is a sectional detail on line 4—4 of Fig. 1.

Fig. 5 is a sectional detail on line 5—5 of 65 Fig. 1.

Fig. 6 is an enlarged detail section taken on line 6—6 of Fig. 1.

Fig. 7 is a sectional detail on line 7—7 of Fig. 1.

Fig. 8 is a plan view of a transversely 70 perforated strip of paper, before plaiting.

Fig. 9 is an end view thereof, after creasing, preliminary to folding.

Fig. 10 is an end view of the completely 75 folded or plaited strip.

As shown on the drawings:

The reference numeral 1, indicates as a whole a table, bed, or supporting frame for the machine which may be mounted in any suitable manner and in any convenient position for use, and said bed plate is provided with forwardly extending arms 2, as clearly shown in Figs. 1 and 2. Secured upon the arm extensions 2, are bearing blocks 3, in which a shaft 4, is journaled, provided with 80 a large gear 5. Also secured upon one of said arm extensions 2, is another bearing block 6, through which a shaft 7, is journaled provided on one end with a driving pulley 8, and on the other end with a pinion 9, meshing with the large gear 5.

Attached upon the bed plate 1, as shown clearly in Fig. 3, are outer guide bars 10, and inner guide bars 11, and slidably therebetween is a carriage consisting of long slide 95 bars 12, each formed with teeth along a portion of the upper edge forming a rack 13, and each at its rear end is provided with an upright 14, rigidly secured thereto in any suitable manner.

Recessed into the respective uprights 14, and slidably associated with each thereof is a block 15, shown in detail in Fig. 7, and each provided with a pin 16, which extends

through a slot 17, in the side wall of its upright 14. Secured to said respective blocks 15, and extending across the machine is a long flat thin feeding plate 18. A coil spring 19, is seated in each of the recessed uprights 14, as shown in detail in Fig. 7, bearing behind the blocks 15, so that said feeding plate 18, is normally thrust forwardly with each of the pins 16, disposed in 10 the forward end of each of the slots 17.

Mounted transversely of the machine at one end thereof is an upright cross-piece 20, slotted to receive engaged therein a plurality of forwardly extending parallel bars 21, and 15 with a clamping bar 22, slotted and fitting over said bars 21, to hold the same secure upon the cross-piece 20. As clearly shown in Fig. 5, the forward ends of each of said bars 21, are fork-shaped as denoted by the 20 reference numeral 23, and extend downwardly and fit over another cross-piece 24, secured transversely on the frame bed 1. Said fork-portions of the bars 21, fit over a transversely extending shaft 25, which at 25 its ends is journaled in bearing blocks 26, mounted one on each side of the machine. Attached between said bearing blocks 26, is a cross-member 27, and secured thereto by clamping bars 28 and 29, on each side of said 30 cross-piece are fork-shaped plates 30, which extend downwardly closely to and in register with the edges of the bars 21. Journaled transversely on the machine in bearing blocks 26, is another shaft 31, above and parallel to the shaft 25, and extending through the fork-shaped plates 30. Said shafts 25 and 31, are provided on their outer ends with intermeshing pinions 32 and 33, respectively, and as shown in Fig. 2, wide idler 35 pinions 34, are mounted on each of the bearing blocks 26, and each meshes with one of the pinions 32, and with a rack 13. Mounted upon each of the respective shafts 25 and 31, are a series of toothed segment folding 40 or creasing rollers 25^a, and 31^a, respectively, the toothed portions of which are adapted to mesh when the shafts are rotated by their 45 intermeshing pinions.

Slidably mounted between the inner guide bars 11, as shown in Figs. 1 and 5, is a flat plate 35, which extends transversely of the machine, and at its forward edge is provided with an upright portion 36. Integral with the upright portion 36, are a plurality of rearwardly extending arms 37, and pivoted thereon as clearly shown in Figs. 1 and 5, are forwardly extending arms 38. The forward upper portion of the face of the upright portion 36, is cored out, and disposed therein is a heating coil 39, shown in Fig. 5, and attached thereover is a heating plate 40, of T-section. Secured on the under portion of the forward ends of the respective arms 38, is an ejecting bar 41, adapted to be thrust 55 downwardly over the heating plate 40. Up-

rights 42, are secured upon the bed frame 1, one at each side and one centrally thereof, as shown in Fig. 1, and secured rigidly therein is a transversely extending cross-bar 43, beneath which the rear end of each of the arms 38, is normally disposed. As shown clearly in the detail view in Fig. 6, each of said arms 38, is normally impelled upwardly in the position shown in Fig. 5, by coiled springs 44, seated in recesses provided therefor in the rearwardly extending arms 37. 75

Secured upon the outer end of the shaft 4, are cam wheels 45, each having a cam groove 46, therein. The ends of the respective slide bars 12, as clearly shown in Figs. 80 1 and 2, are provided with rollers which fit into the respective cam grooves 46, whereby, due to rotation of the cam wheels 45, a certain oscillation or reciprocating movement of said bars 12, is caused to take place. Also 85 mounted upon said shaft 4, are cam wheels 47, each provided with a cam groove 48, as shown in Fig. 5, and rearwardly extending arms 49, integral with the plate 35, are provided with rollers which engage in said cam 90 grooves for a certain operative movement of the plate 35—36.

Fig. 8 shows in plan view a strip of paper denoted by the reference numeral 50, which is transversely perforated, with indicating 95 characters marked upon each perforated division. It is desirable to crinkle or fold said strip of paper into plaited form with the plaits extending longitudinally, that is, at right angles to the lines of perforation there- 100 in, so that the strip when completed will have the form shown in Fig. 10. When the sheet is first thrust between the creasing or folding rolls, it is creased longitudinally as shown in the end view of the strip illustrated in Fig. 9. The finally folded plaited strip is shown in Fig. 10.

Stops 51, are provided on the respective bearing blocks 26, and are so disposed that, when the plate 18, has been brought in position to hold the strip against the heating plate 40, a further forward movement of the plate 18, under the stress of its springs, due to a retraction of the heating plate, will cause the blocks 15, to contact said stops and 115 limit further forward movement thereof.

The operation is as follows:

A strip of paper such as shown in Fig. 8, is laid transversely of the machine upon the top edges of the bars 21, shown in Fig. 1, in 120 front of the forward or feeding edge of the flat plate 18. As the cam wheels 45, rotate, the cam grooves 46, therein, serve to draw the slide bars 12, inwardly thereby sliding the flat plate 18, forwardly over the bars 21, 125 and feeding the paper strip 50, beneath the depending fork-plates 30, and into the field of operation of the segment toothed folder rolls 25^a and 31^a. That is, the plate 18, feeds the strip forwardly sufficiently to cause said 130

rolls to engage with the strip, inasmuch as the rolls have rotated into position for the teeth to engage with the strip, and thereby continue the feeding operation of the strip 5 at the same time creasing the strip longitudinally. This driving motion is imparted to the rolls due to the fact that the arms 12, which slide the plate 18, inwardly are each provided with the rack teeth 13, which drive 10 the respective idler gears 34, on each side of the machine, and which in turn drive the intermeshing pinions 32 and 33.

The operation of the parts is so timed that the toothed portions of said rolls 25^a and 31^a, have passed out of mesh at the time that the plate 18, is introduced therebetween to contact the rear edge of the creased paper strip and continue the feeding movement thereof into and against the heating plate 20 40. Said plate 18, serves to press the creased strip against the heating plate thereby folding the creased strip from the condition shown in Fig. 9, to that shown in Fig. 10. The opposite portions of the cam 25 grooves 46, to that shown in Fig. 2, are then in engagement with the rollers on the ends of the slide bars 12, affording a rest period, and the plate is held against the creased strip. Said plate is held against the folded 30 strip under spring pressure, owing to the fact that the plate 18, is carried on the blocks 15, shown in detail in Fig. 7, which are spring impelled from the uprights 14, secured to the slide bars 12.

35 The stops 51, secured on the outer ends of the bearing blocks 26, are so disposed that said blocks 15, on which the plate 18, is mounted, cannot travel beyond a predetermined distance when the compressive effect on the springs 19, is released, due to 40 the retraction of the heating plate 40, as described in the following.

After the creased and folded paper strips have been held for a time against the heated plate 40, the cam wheels 47, have rotated sufficiently so that the cam grooves 48, therein cause a retraction of the plate 35—36, on which the heating plate is mounted, and at the same time the pivoted arms 50 38, carried thereby are thrust beneath the stationary cross-piece 43, shown in Fig. 5, causing said arms to be depressed as shown in Fig. 6, thereby actuating the bar 41, across the heating plate 40, to eject the 55 folded and creased strip therefrom, and the strip is discharged through the slot 52, in the bed plate. Of course, immediately thereafter, the cam wheels 45, serve to return the feed plate 18, back to initial position, and similarly the cam wheels 47, operate to return the plate 35—36, to normal, ready for another folding operation.

I am aware that various details of construction may be varied through a wide 60 range without departing from the principles

of this invention, and I therefore do not purpose limiting the patent granted otherwise than necessitated by the prior art.

I claim as my invention:

1. A creasing and folding machine comprising a heating plate, mechanism for feeding material toward the heating plate, means creasing said material on its way to the heating plate, said mechanism adapted to compress the creased material against the heating plate, and mechanism retracting said heating plate to permit discharge of the material therefrom. 70

2. A machine for creasing material comprising a feeding mechanism, toothed sector creasing rolls, driving means therefor operated by the feeding mechanism, an abutment plate against which the material is pressed in creased relation after passage between said creasing rolls, and means for 80 retracting said abutment plate from said feeding mechanism to permit discharge of the folded creased material. 85

3. A creasing machine comprising a heated abutment, feeding mechanism adapted to 90 press material toward the same and to compress the creased material thereagainst, and means operating on the material prior to contact with said abutment to crease the same whereby the material is folded as it 95 is pressed against said abutment.

4. A folding and creasing machine comprising an abutment plate, feeding mechanism to thrust material thereagainst, mechanism operating to crease the material on 100 its way toward said abutment plate so as to be folded when pressed thereagainst, and mechanism retracting said abutment plate to permit discharge of the creased folded material. 105

5. A machine of the class described comprising a heated abutment plate, feeding mechanism adapted to feed material toward said plate and to compress the material thereagainst to impart a permanent fold 110 thereto, and means retracting said heated abutment plate from said feeding means to permit discharge of the folded material.

6. In a machine of the class described, an abutment plate, a feeding mechanism adapted to press material thereagainst, creasing devices operating to impart a crease to the material prior to its movement against the abutment plate, and driving connections between said creasing mechanism and said 115 feeding mechanism. 120

7. A machine of the class described comprising a table, a plurality of supporting bars thereon to receive a paper strip deposited thereon, a feeding plate spring impelled in one direction adapted to be moved over said bars to feed a strip of paper therealong, co-acting toothed rollers operating between said bars to impart a crease to the paper moved thereover, a heated abutment 125 130

- plate adapted to receive the creased paper thrust thereagainst by said spring impelled feeding plate to impart a permanent fold to said material, and mechanism acting to retract said abutment plate from said feeding plate to permit discharge of the folded creased material.
8. In a machine of the class described, supporting means for material, a spring controlled feeding plate adapted to be moved thereover to slide the material therewith, co-acting toothed rollers operating to crease the material passed therewith by said feeding plate, operative driving connections between said feeding plate and said creasing rollers, and a heated plate adapted to receive the material thrust thereagainst by said feeding plate to impart a permanent fold thereto, and retractable from said feeding plate thereafter to permit discharge of the creased material.
9. In a machine of the class described, a plurality of bars arranged to receive material laid thereon for movement thereover, a slidable feed member yieldingly held in one adjustment by a spring and adapted to thrust the material along said bars, a plurality of creasing rollers between which said material is passed, and withdrawn thereby from said feed member, and a heating plate beyond the end of said supporting bars against which the creased material is thrust by said feed plate after creasing, and compressed to set a permanent fold in the material.
10. In a machine of the class described, a spring held feed plate, means to receive material laid thereover for movement by said feed plate, creasing rolls between which the material is passed to receive creases formed therein, a heating plate against which the creased material is thrust by said feed plate, and held until a permanent fold is set in the material, mechanism retracting the heating plate, means holding the feed plate from movement toward the retracted heating plate, and mechanism operating to eject the folded material from the retracted heating plate for discharge from the machine.
11. In a machine of the class described, a frame, a shaft journaled thereon, a plurality of cams mounted on said shaft, a feeding mechanism, operative connections between said feeding mechanism and certain of said cams, creasing means for material placed in the machine operatively connected to be driven by said feeding mechanism with each actuation thereof, heating means against which the creased material is pressed to set a fold therein, said heating means operatively connected with certain of said cams for retractive movement after folding and heating of the material, and ejecting mechanism operating to eject the folded material and operatively connected for operation by the retractive movement of said heating means.
12. In a machine of the class described, feeding means for material, cams for actuating the same, rack bar connections between said cams and feeding means, rotatable devices adapted to form a crease in the material and driven by said rack bars with each actuation of the feeding means, a heating mechanism against which the creased material is thrust by said feeding means to set a permanent fold therein, cams for retracting the heating mechanism from said feeding means, and ejecting mechanism mounted on said heating mechanism and actuated across the same with each retraction thereof to eject the folded material from the machine.
13. In a machine of the class described a table for supporting a flat strip, means for creasing the strip and mechanism adapted to coat for pressing the creases together in tight relation.
14. In a machine of the class described mechanism for creasing a sheet and a mechanism for advancing the sheet to the creasing means and acting after the sheet is creased to press the folds together.
15. In a machine of the class described mechanism for creasing a sheet, a mechanism for advancing the sheet to the creasing means and acting after the sheet is creased to press the folds together and means for heating the compressed folds.
16. In a machine of the class described mechanism for creasing a sheet, a mechanism for advancing the sheet to the creasing means and acting after the sheet is creased to press the folds together, means for heating the compressed folds and a positively actuated mechanism for ejecting the folded sheet after the same is heated.
17. A machine for creasing, folding and compressing a paper sheet comprising creasing mechanism and co-acting reciprocating and stationary mechanism for folding and compressing the sheet after being creased.
18. A machine for creasing, folding and compressing a paper sheet comprising creasing mechanism, coacting reciprocating and stationary mechanism for folding and compressing the sheet after being creased, and means for heating the compressed sheet.
19. A machine of the class described comprising an advancing and compressing member, means for actuating the same, means for permitting said member to yield in one direction, creasing members and means for actuating the creasing members.
20. A machine of the class described comprising an advancing and compressing member, means for actuating the same, means for permitting said member to yield in one direction, creasing members, means for ac-

tuating the creasing members, a member adapted to co-act with the aforesaid member to compress said sheet and means for actuating the last named member.

- 5 21. A machine of the class described comprising a supporting and compressing member, means for actuating the same, means for permitting said member to yield in one direction, creasing members, means for actuating the creasing members, a member adapted to co-act with the aforesaid member to compress said sheet, means for actuating the last named member, means for ejecting the compressed sheet and mechanism for operating said ejecting means. 10 22. In a machine of the class described, means for creasing a sheet and means for compressing the sheet together to fold the same into a small package. 20 23. In a machine of the class described, rollers for creasing a sheet longitudinally and mechanism for compressing said sheet transversely. 25 24. A machine for the purpose specified comprising co-acting creasing, folding, compressing and heating mechanism, mechanism for operating said mechanisms to act conjointly, and a device for ejecting the finished product from the machine. 30 25. In a device of the class described, rack bars, a table connected therewith to yield in one direction, creasing mechanism and means connecting the same and the rack bars whereby the table and creasing mechanism act conjointly. 35 26. In a device of the class described, rack bars, a table connected therewith to yield in one direction, creasing mechanism, means connecting the same and the rack bars whereby the table and creasing mechanism act conjointly and a simultaneously movable heating and ejecting device for coacting with said table and creasing mechanism. 40 27. A machine of the class described comprising a support, a feed plate movable thereover, mechanism connected with said plate to positively advance the same, means for stopping the plate after it has traveled a predetermined distance, means permitting the plate to yield relatively of the mechanism for advancing the same adapted to return the plate to normal upon release of the plate from the stopping means, rotating toothed segment creasing rollers and means 45 coacting with the plate to compress an article creased. 28. A machine of the class described comprising a support, a feed plate movable thereover, mechanism connected with said plate to positively advance the same, means for stopping the plate after it has traveled a predetermined distance, means permitting the plate to yield relatively of the mechanism for advancing the same adapted to 50 return the plate to normal upon release of the plate to normal upon release of 55 29. A machine of the class described comprising a support, a feed plate movable thereover, mechanism connected with said plate to positively advance the same, means for stopping the plate after it has traveled a predetermined distance, means permitting the plate to yield relatively of the mechanism for advancing the same adapted to return the plate to normal upon release of the plate from the stopping means, mechanism for coacting with the plate to compress a sheet therebetween and a mechanism between said last named mechanism and said plate for creasing the sheet prior to compression. 60 30. A machine of the class described comprising a support, a feed plate movable thereover, mechanism connected with said plate to positively advance the same, means for stopping the plate after it has traveled a predetermined distance, means permitting the plate to yield relatively of the mechanism for advancing the same adapted to return the plate to normal upon release of the plate from the stopping means, mechanism for coacting with the plate to compress a sheet therebetween, a mechanism between said last named mechanism and said plate for creasing the sheet prior to compression, means for heating the sheet after it is compressed and an ejector for said sheet after being heated. 65 31. A machine of the class described comprising a reciprocating feeding and compressing member and a reciprocating compressing and heating member for coacting therewith. 70 32. A machine of the class described comprising a reciprocating feeding and compressing member, a reciprocating compressing and heating member for coacting therewith and mechanism for crimping the sheet before compressing. 75 33. A machine of the class described comprising a reciprocating feeding and compressing member, a reciprocating compressing and heating member for coacting therewith, mechanism for crimping a sheet before compressing, a pivotally mounted ejector, means for positively actuating the same and a spring for returning the ejector to normal. 80 34. In a machine of the class described coacting creasing rollers having longitudinal teeth on part of their periphery and the remainder of their periphery being plain; and a member adapted to feed a sheet to said rollers to be creased and adapted to pass between the plain portions of the rollers and fold the sheet after being creased. 85 35. In a machine of the class described coacting creasing rollers having longitudinal teeth on part of their periphery and the remainder of their periphery being plain; and a member adapted to feed a sheet to said rollers to be creased and adapted to pass between the plain portions of the rollers and fold the sheet after being creased. 90

- nal teeth on part of their peripheries and the remainder of their peripheries being plain; a member adapted to feed a sheet to said rollers to be creased and adapted to 5 pass between between the plain portions of the rollers to fold the sheet after being creased and an abutting member adapted to coact with said feeding member to compress the sheet.
- 10 36. In a machine of the class described, coacting creasing rollers having longitudinal teeth on part of their peripheries and the remainder of their peripheries being plain, a member adapted to feed a sheet to 15 said rollers to be creased and adapted to pass between the plain portions of the rollers to fold the sheet after being creased, an abutting member adapted to coact with said feeding member to compress the sheet, means 20 for applying heat to the compressed sheet and means for ejecting the heated and compressed sheet.
37. In a machine of the class described a support, co-acting feeding, folding and 25 compressing mechanism, a rotary crimping mechanism acting on a sheet prior to folding and compressing, and an oscillating
- ejecting mechanism for ejecting the finished article from the machine.
38. In a machine of the class described, a support for a sheet, co-acting feeding, folding and compressing mechanism for feeding the sheet over the support and folding and compressing the same, a rotary crimping mechanism for crimping the sheet prior to 35 compression, an oscillating ejecting mechanism, and a heating device adapted to co-act with all of said mechanisms to heat the compressed sheet prior to ejection.
39. In a machine of the character described, the combination of a pair of coöperating crimping elements, a flat grid support for a sheet to be crimped extending between and beyond said crimping elements, and a reciprocating feed plate slidably mounted 45 on said grid support.

In testimony whereof I have hereunto subscribed my name in the presence of two subscribing witnesses.
